(57) **CLAIM**

The ornamental design for a food shaker, as shown and described.

DESCRIPTION

This application is related to application Ser. No. 14/303, 162, filed concurrently herewith, which is incorporated herein by reference.

FIG. 1 is a top, rear and left side perspective view of a food shaker showing our new design;

FIG. 2 is a top plan view thereof;

FIG. 3 is a bottom plan view thereof;

FIG. 4 is a left side elevational view thereof; the right side elevational view being a mirror image thereof;

FIG. 5 is a rear elevational view thereof; and,

FIG. 6 is a front elevational view thereof.

FIG. 7 is a top, rear and left side perspective view of the second embodiment of a food shaker shown in FIG. 1;

FIG. 8 is a top, front and right side perspective view thereof;

FIG. 9 is a top plan view thereof;

FIG. 10 is a bottom plan view thereof;

FIG. 11 is a left side elevation view, the right side being a mirror image thereof;

FIG. 12 is a rear elevation view thereof;

FIG. 13 is a front elevation view thereof;

FIG. 14 is a cross-sectional view taken along line 14-14 of FIG. 9;

FIG. 15 is a top, rear and left side perspective view of the second embodiment of a food shaker with the cap open;

FIG. 16 is a top, front and right side perspective view thereof;

FIG. 17 is a top plan view thereof;

FIG. 18 is a bottom plan view thereof;

FIG. 19 is a rear elevation view thereof;

FIG. 20 is a front elevation view thereof;

FIG. 21 is a left side elevation view, the right side being a mirror image thereof; and,

FIG. 22 is a cross-sectional view taken along line 22-22 of FIG. 17.
